UNITED STATES PATENT OFFICE.

CHARLES F. SMITH, OF NEW BRITAIN, CONNECTICUT, ASSIGNOR TO THE
LANDERS, FRARY & CLARK, OF SAME PLACE.

DESIGN FOR A KNIFE.

SPECIFICATION forming part of Design No. 24,163, dated April 2, 1895.

Application filed December 21, 1894. Serial No. 532,580. Term of patent 7 years.

To all whom it may concern:

Be it known that I, CHARLES F. SMITH, a citizen of the United States, residing at New Britain, in the county of Hartford and State 5 of Connecticut, have invented and produced a new and original Design for a Knife, of which the following is a specification, reference being had to the accompanying drawings, in which—

Figure 1 is a side elevation of a carving knife showing my design. Fig. 2 is a plan view of the same.

A designates the blade which is of a cimeter form, the back 3 of which, as seen in side 5 view, is on a curve that describes a concavity while the edge 4 is convex and curved up to meet the back at the point 5. The heel of the

blade is formed by convex lines 6 at the opposite edges whereby the bolster 7 is at about the longitudinal middle line of the blade. 20 Back of the bolster is the ferrule 8, oval in cross section, but substantially straight in the longitudinal direction of the handle from which bolster the rough surfaced handle B extends; the butt of the handle being cut off obliquely and provided with the ornamental oval shaped plate 9 on said oblique butt. 25

What I claim is—

The design for a knife substantially as herein shown and described.

CHARLES F. SMITH.
